UNITED STATES PATENT OFFICE

91,034

DESIGN FOR A GAME ACCESSORY

Claude R. Kirk, Hollywood, Calif., assignor to
J. Frank Meyer, doing business as Exhibit
Supply Co., Chicago, Ill.

Application August 31, 1933. Serial No. 49,175

Term of patent 3½ years

To all whom it may concern:

Be it known that I, CLAUDE R. KIRK, a citizen of the United States, residing at Hollywood, in the county of Los Angeles, and State of California, have invented a new, original, and ornamental Design for a Game Accessory, of which the following is a specification, reference being had to the accompanying drawing forming part thereof, and in which:

The single figure is a perspective view showing the new design.

I claim:

The ornamental design for a game accessory as shown.

CLAUDE R. KIRK.
